CIGARETTE CASE WITH SECRET POCKET

Simon Knee, Newark, N. J.

Application December 14, 1946, Serial No. 716,337

3 Claims. (Cl. 206—41)

1

This invention relates to cigarette cases or similar containers.

The primary object of the present invention is to provide a cigarette case or similar container with a secret pocket in which paper money or other articles may be placed.

The above object of the invention and other objects ancillary thereto will be fully understood from the following description, reference being had to accompanying drawings which are to be considered as illustrative of the invention but not in limitation thereof.

In the drawings:

Fig. 1 is a perspective view of a cigarette case embodying the present invention, the case being open;

Fig. 2 is a sectional view on a larger scale on the line 2—2 of Fig. 1;

Fig. 3 is a perspective view of part of the case, as shown in Fig. 1, having a removable pull tab;

Fig. 4 is a front perspective view of part of the case showing the secret pocket partly open;

Fig. 5 is an end view of the pull tab.

Referring now to the drawings in detail, the container 10 embodying the present invention, and here illustrated as a cigarette case, comprises the receptacle bodies 12 and 14 hinged to each other as indicated at 16 so that one of these bodies forms a cover for the other in a well-known way. Receptacle body 12 is provided with a latch 18 engageable in the case opening 20 of receptacle body 14 and releasable by a push button 22. As is well understood cigarettes may be placed in either or both of the receptacle bodies 12 and 14 where they are held by the companion elastic bands 24 which are secured at their opposite ends to the frames 26 and 28 respectively of the receptacle bodies. The frames 26 and 28 are metal frames of known construction for the securing thereto of the main or side walls of the respective receptacle bodies the side wall of frame 28 being indicated at 30 in Figs. 1 and 3.

The secret pocket, presently to be described, is provided in the receptacle body 12 but it will be understood that it may also be provided in the receptacle body 14 or, optionally, only in the latter. Referring now more specifically to the receptacle body 12, the main or side wall thereof comprises the outer wall 32 which is preferably formed of leather but which may be formed of any suitable material. Said outer side wall 32 is secured to the frame 26 and forms the inner side of the secret pocket. As shown, the outer wall 32 is of single thickness but it will be understood

2

that it may be provided with an inner lining. An inner wall comprising a layer of covering material of leather or other suitable material is secured in position internally of the body in position over outer wall 32 adjacent the inner side thereof, said inner layer or wall comprising, as here shown, the parts 34 and 36. Preferably said inner wall is formed of the same material or has the same appearance as the inner surface of wall

10 30 of the receptacle body 14. Wall part 36 is secured to the frame at three side edges thereof and has a free edge 38. Wall part 34 is secured in the body 12 preferably at only one side edge thereof as indicated at 40 in Fig. 2 so that said part 34, which is flexibly movable, may be moved away from the outer wall 32 of the case, as illustrated in Fig. 4 to provide access to the contents of the secret pocket. Part 34 has a free end portion 42 defined by the end tabs 44 and by the intermediate tab 46. In the closed condition of the secret pocket illustrated in Figs. 1 to 3, the tabs 44 underlie part 36 of the secret pocket and the intermediate tab 46 overlies part 36 of the secret pocket. Thus, parts 34 and 36 have interengaging portions for releasably holding the flexibly movable part 34 in its normally closed position.

The receptacle body which is provided with the secret pocket includes means which overlies and conceals the free end portion of movable part 34 and the companion end portion of part 36. More particularly, as here shown, said secret-pocket concealing means is constituted by the cigarette-retaining band 24 which is conventionally provided in containers, such as cigarette cases, for holding the cigarettes in place in the case. It will be observed that parts 34 and 36 are relatively dimensioned so that the adjacent ends thereof, which provide the pocket-opening are located in position to be concealed by said band 24. A flat elastic band 48 is secured at its opposite ends to frame 26 in the secret pocket to hold paper money or other papers flat against the inner side of the outer wall 32 of the case, and it will be understood that one or more bills may be folded flat and placed in the secret pocket beneath the part 36 and band 48, said money being covered by parts 34 and 36 of the pocket.

It will be understood that the presence of the secret pocket in the case is not readily ascertainable by one not familiar with the case having said pocket therein as hereinbefore described. In order that the purchaser or owner of the case may become aware of the pocket, the case, in the condition in which it is sold, is provided with a

temporary device for disclosing to the purchaser or owner the presence in the case of the secret pocket. The device provided for this purpose is in the form of a removable pull tab 50 which as illustrated in Fig. 3 carries instructions to inform the purchaser of the presence of the secret pocket and aid the purchaser in locating the secret pocket. Device 50 preferably is formed of cardboard and has a folded end portion 52 which is inserted between part 36 and the tab portion 46 of part 34 of the secret pocket, tab 50 being disposed between the secret pocket and the article-retaining means or band 24 as illustrated in Fig. 2. It will be understood that when the tab 50 is pulled downwardly part 34 of the secret pocket is disengaged from part 36 and moved to its open position, thus revealing the presence of the secret pocket. Once the purchaser or owner of the case has thus initially operated the tab 50, as a result of which the presence of the secret pocket is ascertained, said tab is discarded. Part 34 may be considered as a closure flap or cover for the secret pocket, and device 50 is a pull tab for opening said flap or cover. Although device 50 is a valuable feature of the invention, it may be omitted and if desired supplanted by a circular of instructions which may be furnished to the purchaser of the case.

While I have shown and described the preferred embodiment of my invention it will be understood that the latter may be embodied otherwise than as here specifically illustrated or described and that various changes in the details of construction and in the arrangement of parts may be made without departing from the underlying idea or principles of this invention within the scope of the appended claims.

Having thus described my invention, what I claim and desire to secure by Letters Patent is:

1. A case comprising a receptacle body having an outer main wall, an inner wall positioned internally of said body over the inner side of said outer wall and forming a secret pocket therewith, there being an opening for said pocket, and means in said body concealing said opening from view, said inner wall having a part formed of flexible sheet material and secured to said body so as to be flexibly movable away from said outer wall, while attached in said body, to provide access to the pocket, said part having a free end portion, said inner wall also having a stationary part which is, secured at three side edges thereof to said body and is overlapped at its fourth edge by said free end portion, and an article-retaining band in said body secured at its opposite ends so as to be normally spaced from the outer surface of said inner wall for retaining articles in position against said inner wall in the space between the band and said inner wall, said article-retaining band overlying and concealing said overlapped portions of said movable and stationary parts of said inner wall.

2. A case comprising a receptacle body having

an outer main wall, an inner wall positioned internally of said body over the inner side of said outer wall and forming a secret pocket therewith, there being an opening for said pocket, and means in said body concealing said opening from view, said inner wall having a part formed of flexible sheet material and secured to said body so as to be flexibly movable away from said outer wall, while attached in said body, to provide access to the pocket, said part having a free end portion, said inner wall also having a stationary part which is, secured at three side edges thereof to said body and is overlapped at its fourth edge by said free end portion, and an elastic article-retaining band in said body spaced, in the relaxed condition of the band, from the outer surface of said inner wall for retaining articles in position against said inner wall between the latter and said band, said article-retaining band overlying and concealing said free end portion from view, and interengaging end portions on said parts of said inner wall for releasably holding said movable part in position over said outer wall.

3. A case comprising a receptacle body having an outer main wall, an inner wall positioned internally of said body over the inner side of said outer wall and forming a secret pocket therewith, there being an opening for said pocket, and means in said body concealing said opening from view, said secret pocket having a stationary part and a movable closure flap, and a removable pull-tab having an inner portion disposed freely between said stationary part and said closure flap and thereby releasably connected to said closure flap for moving the latter to its open position, said pull-tab being removably positioned between said inner wall and said concealing means and automatically detachable from said closure flap pursuant to said movement of said flap by said tab.
